US0D1042927S

(12) **United States Design Patent** (10) Patent No.: **US D1,042,927 S**
(45) Date of Patent: ** Sep. 17, 2024

(54) **LAMP**

(71) Applicant: **ZHEJIANG TWINSEL ELECTRONIC TECHNOLOGY CO., LTD.**, Ningbo (CN)

(72) Inventors: **Xueren Zeng**, Ningbo (CN); **Jiawei Li**, Ningbo (CN); **Lizong Hu**, Ningbo (CN); **Lingyan Chen**, Ningbo (CN)

(73) Assignee: **ZHEJIANG TWINSEL ELECTRONIC TECHNOLOGY CO., LTD.**

(**) Term: **15 Years**

(21) Appl. No.: **29/845,897**

(22) Filed: **Jul. 12, 2022**

(30) **Foreign Application Priority Data**

May 20, 2022 (CN) 202230302373.X

(51) LOC (14) Cl. **26-03**

(52) U.S. Cl.

USPC **D26/67**

(58) **Field of Classification Search**

USPC D26/67-70, 72, 73, 80, 85, 89
CPC F21V 21/0824; F21W 2131/109; F21W 2131/10; F21W 2111/02
